UNITED STATES PATENT OFFICE.

LEWIS BENJAMIN DOMAN, OF SYRACUSE, NEW YORK, ASSIGNOR TO THE AMPHION PIANO PLAYER COMPANY, A CORPORATION OF NEW YORK.

SELF-PLAYING MUSICAL INSTRUMENT.

1,326,581.

Specification of Letters Patent.

Patented Dec. 30, 1919.

Application filed July 6, 1915. Serial No. 38,181.

To all whom it may concern:

Be it known that I, LEWIS B. DOMAN, a citizen of the United States of America, and resident of Syracuse, in the county of Onondaga, in the State of New York, have invented new and useful Improvements in Self-Playing Musical Instruments, of which the following, taken in connection with the accompanying drawings, is a full, clear, and exact description.

This invention relates to certain improvements in self-playing musical instruments, and refers more particularly to an expression controlling or tone modulating apparatus, involving the use of a main tension-resisting pneumatic in the connection between the wind-inducing device and sound-producing action for maintaining a maximum air tension in said action corresponding to that in the wind-inducing device, as distinguished from that set forth in my Patent No. 1,075,313, Oct. 7, 1913, and also in my pending application, Serial No. 780,350, filed July 21, 1913, in that the closing action of the main pneumatic tending to restrict communication between the wind-inducing device and sound-producing action is opposed by a yielding resister consisting, in this instance, of a spring of just sufficient force or tension to counteract the effect of the maximum air tension necessary to produce the loudest tones, or fortissimo effects.

The main object is to provide simple means controlled automatically or at will for operating said pneumatic against the action of the resister under different degrees of force for subduing the tone of any note or notes of the musical selection as represented by the note perforations which may be in register with the note ducts of the tracker bar.

In other words, I have sought to associate with the tension-resisting pneumatic a series of auxiliary tone-modifying pneumatics adapted to be placed one by one in communication with the wind-inducing device and arranged in such manner as to exert their individual or collective force upon the main resisting pneumatic against the action of the resister spring, and thereby subdue the tone of such note or notes of the musical selection as may be desired.

Another object is to provide web-controlled means for sequentially opening and closing communication between the auxiliary

pneumatics and wind-inducing device in synchronism with the tracking of the note perforations representing the particular part of the composition which is to be subdued in tone.

Other objects and uses will be brought out in the following description.

In the drawings—

Figure 1 is a perspective view, partly broken away and partly in section, of an expression controlling apparatus embodying the features of my invention.

Fig. 2 is an enlarged vertical sectional view of the device for controlling the operation of the auxiliary pneumatics taken in the plane of line 2—2, Fig. 1.

Fig. 3 is a transverse vertical sectional view of the same device.

Fig. 4 is an enlarged side elevation of a portion of the valve board and one of the pneumatics shown in Fig. 2, together with the slide valve for connecting the ports which lead to the auxiliary pneumatics and to the exhaust port.

Figs. 5 and 6 are enlarged vertical sectional views, taken, respectively, on lines 5—5, and 6—6; Fig. 1.

This apparatus preferably comprises two co-operative units, either of which may be installed in any available part of the instrument case, and for convenience of description, may be termed, respectively, an expression governing device and the other a controller therefor.

The expression governing device comprises a wind chest —1—, a tension-resisting pneumatic —2— and a plurality of, in this instance three, auxiliary tone-modifying pneumatics —3—, —4— and —5—, which together with the pneumatic —2— are mounted side by side upon one and the same side of the wind chest —1—.

This wind chest is divided by a partition —6— into separate compartments or chambers —7— and —8—, the chamber —7— being connected by a flexible pipe —9— to a wind-inducing device —10—, a portion of which is shown in Fig. 1, the other compartment —8— being connected by a flexible pipe —11— to the sound-producing action, not shown.

The pneumatic —2— is connected to the chambers —7— and —8—, through ports —12— and —13— in the adjacent side of the wind chest, as shown in Fig. 2, and

therefore, forms a part of the connection between the wind-inducing device and sound-producing action, the movable side of said pneumatic being provided with a valve 5—14— on its inner face coöperating with the port —12— to vary the air tension in the sound-producing action for tone modulation.

When the pneumatic —2— is full open, the 10 air tension in the action chest will be substantially the same as that in the wind-inducing device for producing corresponding tones but by gradually closing said pneumatic these tones will be gradually subdued.

15 One of the important features of my invention consists in providing means, as a spring —15—, for yieldingly holding the pneumatic —2— full open under a force just sufficient to counteract the effect of the maximum air tension within said pneumatic 20 necessary to produce fortissimo effects by the sound-producing action and to arrange the auxiliary pneumatics in such manner as to exert their individual or collective force 25 upon the tension-resisting pneumatic —2— to partially close the same against the action of the spring —15—, and thereby reduce the air tension in the player action for subduing the tones of selected notes.

30 As illustrated, the movable sides of the auxiliary pneumatics are rigidly connected to the movable side of the pneumatic —2— by a cross bar —16— and it, therefore, follows that if any one of the auxiliary pneumatics is placed in communication with the exhaust or wind-inducing device —10—, a corresponding pressure will be brought to bear upon the movable side of the pneumatic —2— tending to close the same or to restrict 35 communication between the wind-inducing device and sound-producing action, thereby subduing the tone produced by such action.

40 Suitable means is provided for placing these auxiliary pneumatics one by one or 45 in sequence in communication with the exhaust device and thereby modifying the tone of such part or parts of the musical composition as may be desired.

45 For this purpose, I have provided a valve 50 chest —17— with an exhaust chamber —18— and separate valve chambers —19—, the exhaust chamber —18— being connected by a flexible pipe —20— directly to the wind chest —1— of the expression controlling device and, therefore, indirectly to the wind-inducing device —10—, while the valve chambers —19— are connected by ports 55 —21— with the exhaust chamber —18— and are also connected by ports —22— with 60 a chamber —23— which opens to the atmosphere, each of the ports —22— being coaxial with one of the exhaust ports —21—, as shown more clearly in Fig. 2.

65 These ports are controlled by separate valves —24— having suitable stems —24'—

of angular cross section guided in the ports —21— to allow the passage of air through said exhaust ports when uncovered by the valves —24—.

These valves are adapted to be operated 70 by separate primary pneumatics —25— having ports —26— connected by flexible conduits —27— to suitable ducts —28— in a tracker bar —29— across which the music sheet, as —30—, is adapted to travel. 75

This music sheet may be provided with separate rows of apertures —31— and —31'— arranged so as to register with their respective ducts —28— for automatically controlling the operation of the auxiliary 80 pneumatics in a manner presently described, the controlling device being somewhat similar to that set forth in my pending application, Serial No. 78,174, filed February 14, 1916. 85

These auxiliary pneumatics are connected by separate flexible conduits —33—, —34— and —35—, to corresponding ports —33'—, —34'— and —35'— in a valve board —36— forming a part of the valve chest —17—, 90 said valve board —36— being provided with a separate exhaust port —32— connected by a conduit —38— to the exhaust chamber —18—, as shown more clearly in Fig. 3.

These ports —32—, —33'—, —34'— and 95 —35'— are arranged side by side and open through the upper face of the valve board —36— so that the ports —33'—, —34'— and —35'— may be connected one at a time and in sequence with the exhaust port —32— 100 by means of a slide valve —39— which is movable along and upon and is spring-pressed into engagement with the upper face of the valve board —36—, as shown in Fig. 2.

105 Secured to opposite sides of the valve chest —17— are opposed pneumatics —40— and —40'— which communicate with the adjacent valve chambers —19— through separate passages —41— and normally communicate with the atmosphere through the corresponding ports —22—, but may be placed in communication with the exhaust chamber —18— by opening the valves —24— through the medium of the primary 110 pneumatics —25—, as controlled automatically by the perforations —31— and —31'— in the note sheet —30—.

115 The function of the pneumatic —40— is to operate the slide valve —39— step by 120 step in one direction for connecting the ports —33'—, —34'— and —35'— in sequence with the exhaust port —32—, while the other pneumatic —40'— serves to operate the slide valve step by step in the reverse direction 125 for uncovering the ports —35'—, —34'— and —33'— in sequence to the atmosphere, and for this purpose, the slide valve is provided with separate toothed racks —42— and —42'— having their teeth inclined in oppo- 130

site directions for engagement by separate pawls —43— and —43'— carried by the movable sides of the pneumatics —40— and —40'—, respectively, each rack being provided with a plurality of, in this instance three, teeth corresponding to the number of the auxiliary pneumatics —3—, —4— and —5—.

It is to be understood from the foregoing 10 description that the pneumatics —40— and —40'— can only act one at a time and not simultaneously, and that each pneumatic instantly returns to its normal open position after shifting the rack one tooth space at a 15 time, and in order that the valve may be normally free from connection with either pneumatic, the pawls are forced out of engagement with their respective racks by riding upon inclined faces —44— on the upper 20 side of the valve chest along and upon which the pawls move, as shown more clearly in Fig. 1.

Under these conditions, it is possible to 25 operate the slide valve by hand, and for this purpose, it is connected by a rod —45— to a crank shaft —46— which may be journaled upon the instrument case and provided with a finger-piece —47— by which it may be rocked to shift the valve in 30 reverse directions as may be required to produce the desired tone modulation.

Suitable stops —49— are provided for engaging the movable sides of the pneumatics —40— and —40'— and limiting their opening 35 movement so as to assure the movement of the slide valve one tooth space at a time at each operation of the corresponding pneumatic.

Now, if the tone modulating apparatus is 40 to operate automatically through the medium of the note sheet and certain notes or measures of the musical composition are to be played with a subdued effect of, say one degree below fortissimo, then the note sheet 45 will be provided with a single perforation, as —31—, approximately in transverse alignment with the note perforations representing the note or measure at which the subduing effect is to begin, so that when said 50 perforation registers with the corresponding duct —28— in the tracker bar, atmospheric air will be admitted to the corresponding pneumatic —25— to operate the same.

This operation of the primary pneumatic 55 will raise the adjacent valve —24—, thereby closing communication between the corresponding pneumatic as —40— and the atmosphere and opening communication between said pneumatic and the exhaust chamber —18— through the open port —21— which causes instantaneous collapse or closing of said pneumatic —40— and, therefore, causes its pawl —43— to engage the corresponding rack and shift the slide valve 60 —39— one tooth space, or sufficient to con-

nnect the port —33'— and its corresponding auxiliary pneumatic —3— with the exhaust port —32—.

This places the pneumatic —3— under the influence of the exhaust device which 70 partially closes the tension-resisting pneumatic —2— against the action of the spring —15—, thus reducing the air tension in the sound-producing action to subdue the tone of the instrument one degree. 75

As soon as the single aperture —31— mentioned has passed the duct —28— in the tracker bar to cut off communication between the primary pneumatic and atmosphere, the corresponding valve —24— automatically closes communication between the pneumatic —40— and exhaust chamber —18— and opens communication between said pneumatic and the atmosphere, causing such pneumatic to instantly open and to 85 draw its pawl back ready for a repetition of the operation, previously described.

In like manner, if another aperture —31— is provided in the note sheet to succeed the first one, it is evident that the slide valve 90 —39— will be shifted another tooth space to embrace the two of the ports —33'— and —34'— and, thereby cause the operation of another one of the auxiliary pneumatics as —4—. 95

Again, if three apertures —31— succeed each other in the note sheet, the third auxiliary pneumatic —5— will be brought into action, each one tending to move the tension-resisting pneumatic —2— nearer to its 100 closed position for further subduing the tone, the action of the three auxiliary pneumatics being sufficient, in this instance, to modulate the tone from fortissimo to pianissimo, step by step. 105

In reverse manner, the slide valve may return to its starting position step by step through the medium of the pneumatic —40'— and its pawl —43'— to successively cut off communication between the exhaust 110 device and auxiliary pneumatics —5—, —4— and —3— and to similarly connect said auxiliary pneumatics with the atmosphere.

It is now evident that if the note sheet is not provided with these perforations —31— 115 and —31'—, the instrument will be played with full fortissimo effects, but the tone may be modulated at will through the medium of the finger-piece —47— and its connection with the slide valve through the rod 120 —45— by simply rocking the finger-piece in one direction or the other at the proper time to produce the desired tone effects.

The same apparatus may, therefore, be used for either automatic or voluntary control of the tone modulation, and although I have shown only three of the auxiliary pneumatics —3—, —4— and —5—, it is evident that the number may be increased or diminished and that other changes may be made 125 130

in the detail of construction and arrangement of the various elements without departing from the spirit of my invention.

By setting the governing pneumatic —2—
5 so as to remain full open under all varying conditions of air tension below that required to produce fortissimo effects, it is evident that the tension in the governing pneumatic and, therefore, that in the sound-producing
10 action will vary with the varying conditions in the wind chest —1— as produced by variations in the power and speed of action of the pumping bellows.

This condition is highly important and
15 of great advantage in the operation of this class of instruments because it enables the operator to vary the expression from pianissimo to fortissimo through the medium of the pedals without necessitating the operation of any of the other expression-controlling devices, such as the assister pneumatics —3—, —4— and —5—.

Another advantage is that the operator may maintain any degree of air tension in
25 the sound-producing action above pianissimo by means of the pedals or other pumping operating device, and then at any time while such tension is being maintained, may subdue the tones by causing the operation of
30 any one or more of the pneumatics —3—, —4— and —5— in the manner described.

What I claim is:

1. In a self-playing musical instrument, an expression-governing device including a
35 pneumatic and yielding means for opening said pneumatic with a predetermined force sufficient to cause the instrument to play with fortissimo effect, in combination with separate auxiliary pneumatics acting upon
40 the first-named pneumatic against the action of said opening means, atmosphere ports communicating with their respective auxiliary pneumatics, an exhaust port, and means for connecting the atmosphere ports
45 one by one in sequence with the exhaust port and cutting off communication between such atmosphere ports and the atmosphere.

2. In a self-playing musical instrument, an expression-governing device including a
50 pneumatic and means for opening the same with a predetermined force sufficient to cause the instrument to operate with fortissimo effect, in combination with a plurality of auxiliary pneumatics acting upon the first-named pneumatic in opposition to said opening means, each normally communicating with the atmosphere through separate ports, an exhaust port, a valve normally embracing the exhaust port and movable to embrace the
55 atmosphere ports in sequence with the exhaust port for sequentially connecting the auxiliary pneumatics with said exhaust port, and means for operating the valve.

3. In a self-playing musical instrument,
60 an expression-governing device including a

pneumatic and means for opening the same under a predetermined force, an auxiliary pneumatic acting upon the first-named pneumatic in opposition to said opening means and normally communicating with an atmospheric port, an exhaust port, a valve for connecting and disconnecting the atmospheric port to and from the exhaust port and means including a pair of pneumatics for operating said valve in reverse directions. 70 75

4. In a self-playing musical instrument, an expression-governing device including a pneumatic and means for opening the same under a predetermined force sufficient to resist the tendency to close under the air tension therein when playing with fortissimo effect, in combination with an auxiliary pneumatic acting upon the first-named pneumatic in opposition to said opening means and normally communicating with an atmosphere port, an exhaust port, a valve for connecting and disconnecting the atmosphere port to and from the exhaust port, separate pneumatics for operating the valve in reverse directions and normally communicating with the atmosphere through separate ports, an exhaust chamber, and automatically operating means including a note sheet for alternately placing each of said pneumatics in communication with the atmosphere port and with the exhaust chamber. 80 85 90

5. In a self-playing musical instrument, an expression-governing device including a pneumatic and means for opening the same under a predetermined force, in combination with auxiliary pneumatics acting upon the first-named pneumatic in opposition to said opening means and normally communicating with the atmosphere through separate ports, a reversibly movable slide valve for connecting and disconnecting the atmosphere ports one by one with and from the exhaust port and provided with reversely arranged toothed racks, an exhaust 100 105 chamber, separate valve chambers having ports opening to atmosphere and other ports communicating with the exhaust chamber, valves controlling said ports and normally closing the exhaust ports, separate primary 110 pneumatics for operating the valves, additional pneumatics having separate pawls co-operating with said racks for shifting the slide valve step by step in reverse directions, a tracker bar having ducts communicating 115 120 with the primary pneumatics, and a note sheet having perforations co-operating with said ducts to control the operation of said primary pneumatics.

In witness whereof I have hereunto set my hand this 23rd day of June, 1915.

LEWIS BENJAMIN DOMAN.
